UNITED STATES PATENT OFFICE

JENNIE G. MOWELL, OF KINGSTON, NEW YORK

PULL-CORD FASTENER FOR WINDOW SHADES

Application filed July 23, 1928. Serial No. 294,888.

The present invention pertains to improvements in means for attaching pull cords to window shades, and the same accomplishes its most important object by means of a novel 5 fastener which may be detachably connected to a window shade, thus permitting the pull cord to be removed from the shade, for the purpose of being cleaned, or replaced.

Another important object is to provide a 10 fastener for pull cords, wherein means is provided for supporting an ornamental body to conceal the fastener when properly adjusted on the shade.

Still another object of importance, resides 15 in the particular construction of the fastener, which is constructed of a single strand of relatively stiff spring material, and bent in a novel manner to provide both means for supporting the ornamental body and for the 20 attachment of a pull cord thereto.

Other important objects and advantages of the invention will become apparent after reading the following specification and claims.

25 In the drawings:—

Figure 1 represents a fragmentary front elevation of a conventional window shade, equipped with the novel feature fastener, which is partially concealed by the presence 30 of the ornamental body supported thereon.

Fig. 2 is a vertical sectional view through the lower portion of the conventional window shade, and disclosing in side elevation, the novel fastener with a pull cord fragmentarily 35 shown attached thereto, and

Fig. 3 is a perspective view of the fastener without the ornamental body and pull cord attached thereto.

Referring to the drawings, wherein like numerals designate like parts, a conventional window shade is designated in the drawing by A, and is provided with the usual pocket portion B, for receiving the stiffening stick C, shown in Fig. 2 of the drawings.

40 In carrying out the present invention, a single strand of relatively stiff spring material, such as is generally referred to by the numeral 1 is bent angularly by twisting an intermediate portion thereof to provide a loop 45

50 2. One leg portion 3 is substantially shorter

than its complementary leg and is pointed at its extremity.

The elongated leg 4 is bent at an intermediate point to provide a second loop, while its end portion is disposed laterally toward the short leg 3. The intermediacy of the end portion of the elongated leg 4 is formed to provide a third loop while the extremity thereof is bent to provide a hook 7 engageable around the short leg 3.

As is clearly shown in Fig. 2, an ornamental body 8 is adapted to be attached between the loops 2 and 5, while the pull cord 9, which may be provided with the usual toggle 10 is knotted at its upper end to the loop 6.

Obviously, the short pointed leg 3 serves as a pin and is adapted to be inserted through the shade material and disposed at the rear of the pocketed portion B of the shade in the manner shown in Fig. 2, after which the hook 7 is engaged with the same, to secure the fastener properly to the shade.

It is to be understood that no limitation is to be placed on the ornamental body 8, nor the type of pull cord employed, as many pleasing designs can be employed without departing from the spirit of the invention or the scope of the appended claims.

Having thus described my invention, what I claim as new is:—

1. In a pull cord fastener of the character described comprising, an elongated strand of relatively springy material, said strand being bent at an intermediate point to provide a loop, the leg portions of said strand being disposed in outwardly diverged relation, one of said legs being longer than the other, said elongated leg being formed with means to provide a second loop, the outer end portion of said elongated leg being disposed laterally toward the short leg and provided with a third loop in its intermediacy, the end of said elongated leg being formed to provide a hook, the end of the shorter leg being pointed, the first and second mentioned loops being adapted to support an ornamental body, while a pull cord may be attached to the third mentioned loop.

2. In a pull cord fastener of the character described comprising a fastener constructed

of a single strand of relatively springy material, said strand being bent angularly, the end portion of one leg being bent laterally and provided with a hook for engagement with the
5 other leg, means on said laterally bent portion to which the pull cord may be attached, and means on the strand for supporting an ornamental body.

In testimony whereof I affix my signature.
